(57) **CLAIM**

The ornamental design for an electronic console, as shown and described.

DESCRIPTION

FIG. 1 is an isometric view of an electronic console showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the encircled portion labeled as **8** in FIG. 1;

FIG. 9 is an enlarged view of the encircled portion labeled as **9** in FIG. 4;

FIG. 10 is an enlarged view of the encircled portion labeled as **10** in FIG. 5; and,

FIG. 11 is an enlarged view of the encircled portion labeled as **11** in FIG. 6.

The broken lines in the drawings depict portions of the “game controller” that form no part of the claimed design. The uneven-length broken lines showing of the encircled portions in FIGS. 1, 4-6, and 8-11 show boundaries of enlarged views, and form no part of the claim design.
